UNITED STATES PATENT OFFICE.

JOHN C. LYONS, OF McCOMB, MISSISSIPPI.

ENGINEER'S BRAKE-VALVE.

SPECIFICATION forming part of Letters Patent No. 772,422, dated October 18, 1904.

Application filed February 27, 1904. Serial No. 195,580. (No model.)

To all whom it may concern:

Be it known that I, JOHN C. LYONS, a citizen of the United States, residing at McComb, in the county of Pike, State of Mississippi, have 5 invented certain new and useful Improvements in Engineers' Brake-Valves, of which the following is a specification, reference being had therein to the accompanying drawings.

This invention relates to an engineer's brake-valve, and particularly to means for reducing 10 the pressure upon the train-line to different degrees and controlling said pressure.

The invention has for an object to improve the construction and arrangement of the brake-valve so as to utilize a series of reduction-reservoirs adapted to be independently or successively thrown into communication with the 15 train-line for the purpose of reducing the pressure of air therein to any desired extent or 20 for completely exhausting said pressure.

Another object of the invention is to improve the construction of the valve-casing co-operating with the equalizing-piston and to provide the same with properly-disposed ports 25 to coöperate with a rotary cylindrical valve mounted in said casing.

Other and further objects and advantages of the invention will be hereinafter set forth and the novel features thereof defined by the 30 appended claims.

In the drawings, Figure 1 is a central vertical section of the valve; Fig. 2, a similar section on the line 2 2 of Fig. 1; Fig. 3, a horizontal section on the line 3 3 of Fig. 1; Fig. 35 4, a plan of the reducing-reservoirs, the valve-casing above the same being removed; Fig. 5, a vertical section through the valve at right angles to Fig. 1; and Fig. 6, a bottom plan of the valve, showing the ports and passages 40 therein.

Like letters of reference indicate like parts throughout the several figures of the drawings.

The letter A designates the casing within which the equalizing-piston A' is disposed, 45 said piston being in connection with the train-pipe A² and with the passage A³, leading to the equalizing-reservoir, said passage being provided with a gage connection A⁴. Coöperating with the stem of the equalizing-piston 50 is an exhaust-passage A⁵, while at the opposite

side of the casing the usual pipe connection A⁶ from the main reservoir is provided and also a connection therefrom at A⁷ to the pump governor and gage. Extending upward from the cylinder of the equalizing-piston a communicating passage A⁸ is provided and extends to the valve-ports. The parts thus far described may be of any ordinary construction, and those illustrated are of a construction in common use.

At the upper part of the cylinder of the equalizing-piston A' and forming the top thereto is a reduction-reservoir B, which comprises a series of independent chambers B', which may be of equal or varying capacities 55 and adapted to permit an expansion of the air under pressure in the train-pipe to such an extent as to reduce the pressure thereon. At the opposite sides of this reservoir passages B² and B³ are provided therethrough, which communicate, respectively, with the passages A⁶ and A⁸ in the casing for the equalizing-piston. Central of these chambers B' a passage B⁴ is provided, which communicates at its lower end with the equalizing-piston and at its upper 60 end with the controlling-valve. The reservoir is also provided with any suitable number of bolt-receiving sockets B⁵, as shown in Fig. 4. Disposed upon this equalizing-reservoir and forming a closure at the top thereof is a casing C for the rotary valve D. This casing is 65 provided with a feed-passage C', communicating with the main reservoir, and provided at its upper portion with the port C², communicating with the interior of the valve D. At the opposite side an exhaust-port C³ extends through the casing, while below this port a communicating passage C⁴ extends from the valve to the train-line by the passage A⁸. Extending from each of the reduction-chambers 70 B' is a communicating passage C⁵, as shown in Fig. 3, adapted to communicate with suitable ports or passages in the valve D when the same is properly shifted. The casing C is also provided with the excess-pressure valve 75 C⁶, communicating with the rotary valve D by means of a passage C⁷ and with the equalizing-piston by means of a passage C⁸, communicating with the groove D' in the face of the valve D, which groove is also in commun- 80

nication with a passage C⁹, leading to the passage B⁴, which extends to the equalizing-piston. The passage C¹⁰ also extends from the excess-pressure valve to the train-line A⁸, Fig. 3.

- 5 The rotary valve D may be of any desired construction; but a preferable form thereof is herein shown and may comprise a frame D², having at its opposite sides pintles D³, to 10 which a yoke or other handle D⁴ may be applied, said handle being adapted to coöperate with the notched segment D⁵ of any suitable construction. The notches thereon are used to 15 designate the different positions of the valve. The lower portion of the valve is provided with ports D⁶, extending therethrough, while the interior face is formed with a flange D⁷, adapted to carry an annular packing D⁸, which is normally forced outward therefrom by 20 means of springs D⁹, disposed between the flange and packing. The valve is also provided at one side with an exhaust-cavity D¹⁰ and with a port E therethrough to communicate with the equalizing-piston and with the 25 grooved ports or channels E', upon its periphery, adapted to communicate with all of the passages from the reduction-chambers and release the pressure therefrom. The periphery of the valve is also provided with a series of 30 grooved ports E², adapted in the movement of the valve to successively communicate between the passages from the reducing-chambers and the equalizing-piston to reduce the train-line pressure.
- 35 The valve herein illustrated is adapted to be shifted to eight different positions, which are numerically indicated in Fig. 1 as corresponding to the notches of the segment, so as to facilitate the description of the operation 40 of my invention.

In the operation of the invention it will be seen that the pressure upon the train-pipe line is reduced successively by the reduction-chambers, which may be of any desired area 45 relative to the equalizing-reservoir—for instance, one chamber may be one-eleventh of the capacity of the equalizing-reservoir, another one-twelfth thereof, another one-thirteenth thereof, and the remaining one one-fifteenth thereof, which in the arrangement 50 illustrated would make a five-pound reduction in pressure as each of the chambers is brought into communication with the train-pipe-line. For illustration there may 55 be seventy pounds air-pressure in the train-line and equalizing-reservoir, the latter containing seventy cubic inches of air. If the brake-handle be placed in the fourth position, (indicated in Fig. 1,) it will bring the valve- 60 port in communication with one of the chambers, thus reducing the pressure in the equalizing-reservoir five pounds and causing the equalizing-piston to let five pounds of air-pressure from the train-line to apply the 65 brake. If placed in the fifth position, an-

other chamber is added, thus effecting a ten-pound reduction, and the same with the sixth and seventh positions, effecting a reduction of fifteen and twenty pounds, respectively. When the brake-handle is in the first position, the brakes are released as the air coming from the main reservoir passes through the valve into the train-pipe and to the top of the equalizing-piston, thus filling the equalizing-reservoir. When shifted to the second position, which is that for the train when running, the air passes from the valve to and through the excess-pressure valve, thence into the train-line, and also through the port to the top of the equalizing-piston. In this position the excess-pressure valve is retained under a spring-pressure of, for instance, twenty pounds to the square inch resistance, so that the reservoir-pressure will be twenty pounds greater than the train-line pressure and the 85 excess-valve will be lifted for the passage of air to the train-line, and a proper pressure thus maintained upon the brake system. In the third position the ports lap, thus closing all communication from the rotary valve. In 90 the fourth, fifth, sixth, and seventh positions a reduction of five, ten, fifteen, and twenty pounds, respectively, is effected, as before described. In the eighth position, which is provided for emergencies, the exhaust-chamber upon the periphery of the valve is brought into communication with the exhaust-port in the casing and the train-line, thus releasing 95 all the pressure to the atmosphere. If the handle be moved from position 2 to 6, a fifteen-pound reduction in pressure will be effected, as in that position three of the chambers will be filled, while a movement to the seventh position fills four chambers and effects a twenty-pound reduction. When the handle 100 is again restored to position 1, all of the ports from the chambers connect with the grooved passages upon the periphery of the valve and the chambers exhaust their air to the atmosphere. If it should be desired to release the 110 air-pressure less than five pounds at one time, it can be accomplished by placing the handle in position 5, thus securing a ten-pound reduction and then moving it to position 6 until two and one-half pounds is indicated by the 115 gage, when the handle will be brought back to the fifth position, thus maintaining a reduction of twelve and one-half pounds in pressure.

It is obvious that changes may be made in the details of construction and configuration, as well as in the air-brake system to which the invention is applied, without departing from the spirit thereof as defined by the appended claims.

Having described my invention and set forth its merits, what I claim as new, and desire to secure by Letters Patent, is—

1. In a brake-valve, a separable casing provided with a series of independent reduction-

chambers, a removable cover-plate disposed between said chambers and valve and having independent passages therethrough from each chamber to said valve, means for securing said valve, reduction-chambers and plate in contact with each other, and a train-line communicating with said chambers through said valve.

2. In a brake-valve, an equalizing-piston cylinder, a series of independent reduction-chambers disposed to close one end of said cylinder, a plate above said chambers having independent passages to said valve, a train-line communicating with said chambers through said valve, and a main pressure-line communicating with said valve.

3. In a brake-valve, a casing having diametrically-disposed partitions having passages therein and forming a series of independent reduction-chambers having independent communication with said valve, a train-line communicating with said chambers through said valve, a main pressure-line communicating with said valve, and an equalizing-piston and reservoir communicating with said valve through a passage in said partitions.

4. In a brake-valve, a valve-casing having passages therethrough, a series of independent reduction-chambers disposed beneath said casing and having independent communication with said valve through said passages, a train-line communicating with said chambers through said valve, a main pressure-line communicating with said valve, an equalizing piston and cylinder disposed beneath said chambers and communicating with said valve independent of the train-line, and an excess pressure-valve communicating with said brake-valve and with the train-line and the equalizing-piston.

5. In a brake-valve, a reduction-reservoir consisting of a series of separate chambers, a valve-casing provided with a plate to close the top of said reservoir and having independent ports leading to said chambers, a hollow rotary valve within said casing, having ports to register with the casing-ports, a line from the main reservoir to the interior of said valve, and a train-pipe line communicating with the port in said valve.

6. In a brake-valve, a reduction-reservoir consisting of a series of separate chambers, a valve-casing provided with a plate to close the top of said reservoir and having independent ports leading to said chambers, a rotary valve within said casing, having a pressure-chamber therein and ports to register with the casing-ports, a line from the main reservoir to said valve at the top of its casing, a train-pipe line communicating with a port in said valve, an exhaust-cavity in the periphery of said valve, and a port provided in the casing to establish communication through the cavity with the train-pipe.

65 7. In a brake-valve, a casing, a rotary cy-

lindrical valve therein having passages upon its periphery and ports therethrough, an interior shoulder within said valve, an annular packing supported upon said shoulder, and means for forcing said packing outward from 70 said shoulder.

8. In a brake-valve, the combination with a train-pipe line, of an equalizing cylinder and piston, a reduction-reservoir comprising a series of independent chambers and closing the 75 top of said cylinder, and a valve provided with means for establishing communication between the train-pipe line and one or more of said chambers.

9. In a brake-valve, the combination with a 80 train-pipe line, of an equalizing cylinder and piston, a reduction-reservoir comprising a series of independent chambers and closing the top of said cylinder, a valve having a plate to close the chambers and provided with means 85 for establishing communication between the train-pipe line and one or more of said chambers, and means carried by said valve for reducing the pressure within all of said chambers.

90 10. In a brake-valve, the combination with a train-pipe line, of a reduction-reservoir comprising independent chambers, and a valve open at its top and having its lower wall provided with ports for successively bringing 95 said chambers into communication with the train-pipe line.

11. In a brake-valve, the combination with a train-pipe line, of a reduction-reservoir comprising independent chambers, a valve provided with a pressure-chamber therein and means for successively bringing said reduction-chambers into communication with the train-pipe line and subsequently releasing the pressure from the said line, and a pressure-line 100 communicating with said pressure-chamber.

105 12. In a brake-valve, a reduction-reservoir comprising independent chambers having passages extending therefrom, and a rotary valve 110 having an interior pressure-chamber communicating with the pressure-reservoir and a passage upon its periphery adapted to communicate with all of the ports from said chambers to exhaust the same.

115 13. In a brake-valve, a reduction-reservoir comprising independent chambers having passages extending therefrom, a rotary valve having an interior pressure-chamber communicating with a pressure-reservoir and a passage 120 upon its periphery adapted to communicate with all of the ports from said chambers to exhaust the same, and passages provided upon the periphery of said valve for successively establishing communication between the interior thereof and said chambers.

125 14. In a brake-valve, a reduction-reservoir comprising independent chambers having passages extending therefrom, a rotary valve having an interior pressure-chamber commun- 130

cating with a pressure-reservoir and a passage upon its periphery adapted to communicate with all of the ports from said chambers to exhaust the same, passages provided upon the periphery of said valve for successively establishing communication between the interior thereof and said chambers, an equalizing-piston having a passage extending from its cylinder through the reduction-reservoir to the valve, and a passage extending therefrom to a port communicating with the interior of said valve.

15. In a brake-valve, a reduction-reservoir comprising independent chambers having passages extending therefrom, a rotary valve having a passage upon its periphery adapted to communicate with all of the ports from said chambers to exhaust the same, passages provided upon the periphery of said valve for successively establishing communication between the interior thereof and said chambers, an equalizing-piston, a passage extending therefrom to a port communicating with the interior of said valve, an exhaust-cavity provided in one wall of said valve to communicate with the port through the casing thereof, and a reservoir communicating with the upper portion of said valve.

20. In a brake-valve, a reduction-reservoir comprising independent chambers having passages extending therefrom, a rotary valve having a passage upon its periphery adapted to communicate with all of the ports from said chambers to exhaust the same, passages pro-

vided upon the periphery of said valve for 35 successively establishing communication between the interior thereof and said chambers, an equalizing-piston, a passage extending therefrom to a port communicating with the interior of said valve, an exhaust-cavity provided in one wall of said valve to communicate with a port through the casing thereof, a reservoir communicating with the upper portion of said valve, an excess-pressure valve, and passages extending therefrom to the train-pipe line and to the equalizing-reservoir through a chamber formed upon the periphery of said valve. 40 45

17. In a brake-valve, a casing, a rotary cylindrical ported valve therein, an interior shoulder within said valve, an annular packing-ring supported upon said shoulder, and means for forcing said ring away from said shoulder. 50

18. In a brake-valve, a casing, a rotary cylindrical ported valve therein, an inwardly-extending shoulder within said valve, an annular packing-ring slidably mounted within the valve, and springs disposed between said shoulder and ring for forcing them away from each other. 55 60

In testimony whereof I affix my signature in presence of two witnesses.
